UNITED STATES PATENT OFFICE.

DAVY VANCE SICKMAN, OF DENVER, COLORADO.

HYDRAULIC CARTRIDGE.

1,243,991.

Specification of Letters Patent. Patented Oct. 23, 1917.

Application filed September 13, 1915. Serial No. 50,857.

To all whom it may concern:

Be it known that I, DAVY VANCE SICKMAN, a citizen of the United States, residing at the city and county of Denver and State of Colorado, have invented certain new and useful Improvements in Hydraulic Cartridges; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in hydraulic cartridges of the class employed in breaking down coal or other material in mines, through the medium of fluid pressure, water being generally employed for this purpose.

My present improvement embodies as illustrated in the drawing a construction in which the bar of the cartridge is equipped with pistolets each composed of two members occupying compartments spaced by an interposed wall. When the cartridge is in use these piston members are projected in opposite directions, the water pressure reacting upon the interposed stationary wall while the piston members are actuated and serve to break down the material.

In my present construction the interposed wall is provided with ports and passages for the introduction of the water or other fluid to the pressure surfaces of the piston members. By virtue of this construction, the part in which the fluid passages are formed, is stationary as distinguished from the movable columns or auxiliary pistons through which the fluid passes, in the construction disclosed, for instance in my application, Serial No. 38,856, filed July 9, 1915.

An additional feature of novelty consists in the construction whereby each piston member is equipped with valves for automatically cutting off the supply of water from the pressure surfaces of the piston members, when the latter have reached the desired limit of outward movement. In my aforesaid application the construction embodies means for automatically cutting off the supply of fluid to the larger piston

member, but the smaller member is not so equipped. In my present construction the fluid is automatically cut off from the pressure surfaces of both members.

Still another feature of novelty in my present construction, consists in the securing of the interposed wall by means of pins which are passed horizontally through openings formed in the partitions of the bar which separate the piston chambers from each other. It should be stated that this construction is more especially adapted for use in connection with the elongated or ellipsoidal shape of pistons, since where this shape of piston is employed, it is impossible to connect the interposed wall with the bar by screwing it into place, since the opening in which it is inserted, as well as the partition itself is elongated instead of cylindrical.

Having briefly outlined my improved construction I will proceed to describe the same in detail, reference being made to the accompanying drawing in which is illustrated an embodiment thereof. In this drawing,

Fig. 1 is a fragmentary underneath view of a cartridge equipped with my improvements.

Fig. 2 is a top plan view of the bottom plate of the interposed wall shown in detail.

Fig. 3 is a vertical section taken through the cartridge on the line 3—5, Fig. 1, the parts being shown on a larger scale.

Fig. 4 is a similar view of the smaller piston member shown in detail.

Fig. 5 is a section also taken on the line 3—5, Fig. 1, shown on the same scale as Fig. 3 but with the piston members fully projected.

Fig. 6 is a fragmentary top plan view of the bar showing the interposed wall of one piston chamber in place, the piston being removed. In this view the interposed wall is viewed in the direction indicated by arrow 6, Fig. 8.

Fig. 7 is an underneath view of the same portion of the bar disclosed in Fig. 6, with the interposed wall in place but with the lower piston member removed. In this view the interposed wall is viewed in the direction indicated by arrow 7, Fig. 8.

Fig. 8 is a central vertical section taken through the interposed wall shown in detail and on the same scale as Fig. 5.

Fig. 9 is a cross section taken through the 5 bar on the line 9—9, Fig. 6.

Fig. 10 is a side elevation partly in section showing the top nut of the centrally located valve chamber of the interposed wall.

Fig. 11 is a top view of the same or a 10 view looking in the direction of arrow 11, Fig. 10.

Fig. 12 is a vertical section similar to Fig. 3 but illustrating a modified form of construction.

15 Fig. 13 is a similar view of the same construction but with the piston members projected.

20 Figs. 14 and 15 are detail end views respectively illustrating the piston members 3 and 5.

The same reference characters indicate the same parts in all the views,—

Referring first more particularly to the 25 construction shown in Figs. 1 to 9 inclusive, let the numeral 5 designate the bar of the cartridge which may be of any desired length. These bars are usually of such length as to hold or carry a plurality of pistons. In the drawing the bar wherever 30 shown is broken away to indicate that it may be of any desired length. As the construction of a single piston together with the portion of the cartridge bar to which it 35 is applied, is the same regardless of the number of pistons used, a description of a single piston portion of the bar will be sufficient for all purposes. The term piston as here employed, and referring particularly 40 to the construction disclosed in the drawing, is composed of two members the lower or larger member being designated by the numeral 6 and the upper or smaller member by the numeral 7. The terms upper and 45 lower as applied to these members are employed for the reason that generally the cartridge bar will be in such position that the piston 7 will be uppermost and the piston 6 lowermost when projected. When the 50 two piston members are not projected or are in the normal position, they are telescoped and to a large extent occupy the same vertical position, though even when in the telescoped relation, a part of the lower member 55 extends below the lowest part of the upper member, and the highest part of the upper member extends considerably above the corresponding part of the lower member.

These two piston members are arranged 60 in co-operative relation with an interposed wall 8 (see Fig. 8), which is secured within a chamber 9 formed in the bar, the said wall serving to separate this chamber into two compartments 10 and 12, the member 6 occupying one compartment and the member

7 the other compartment. This wall in top plan view is rectangular in outline as shown in Fig. 6, its extremities 13 being countersunk, so to speak, in relatively shallow cavities 14 formed in the bar, while the exterior outline of this partition is ellipsoidal or provided with rounded or curved extremities. These ends 13 of the interposed wall are provided with horizontally disposed perforations 15 which are arranged to register 75 with similar perforations 16 formed in partitions 17 which separate any chamber in which an interposed wall is located, from the two adjacent chambers. In the case of a terminal chamber, the corresponding end portion of the bar will contain the perforations 16 as will be readily understood by reference to Fig. 1.

In the case of two adjacent chambers, the 80 adjacent perforations 15 of the two walls, will be in register with the perforations 16 of the partition of the bar, and the same securing pin 18 will be employed for fastening the interposed walls in place. These pins will be so secured as to form fluid tight 85 joints.

Each interposed wall contains three valve chambers one of which is centrally located and designated 19 while the two others each of which is designated 20, are arranged on 90 opposite sides of the central chamber. The chamber 19 is provided at its top with a nut 21 which is interiorly threaded and applied to exterior threads formed on the top of the chamber casing as shown at 22. This 100 nut has a central opening 23 (see Fig. 11) said opening being enlarged by vertically disposed recesses 24. The lower extremities of the chamber 19, is closed as shown at 25, the casing of this chamber being 105 threaded into place in the lower part or body 26 of the interposed wall as shown at 27. The upper extremity of each chamber 20 is closed as shown at 28 while its lower extremity is provided with an 110 opening 29 formed in a nut 30 which is threaded into place in the lower part 26 of the wall as shown at 31. Each of these openings 29 is also enlarged by the formation of vertical grooves or recesses 32. Between the upper face of each nut and the adjacent surface of the part 26 of the wall, is located a gasket 33. A similar gasket 34 is also located between the nut 21 and the upper extremity of the casing of the chamber 120 19.

To the lower surface of the bottom 26 of the interposed wall, is applied a plate 35 which is secured in place by screws 36. This plate holds in place a relatively large 125 gasket 37 which extends entirely around the bottom 26 of the interposed wall and forms a fluid tight joint between the bottom of the wall and the adjacent inner surface 38 of the piston member 6. The casings of 130

the chamber 19 and the two chambers 20, extend upwardly from the bottom 26 of the wall 8 into the relatively large compartment 12 which receives the piston member 7. This member is provided at its lower extremity with a gasket 39 which extends entirely around the piston member and is held in place by a plate 40 secured by screws 41. The piston member 7 has chambers 42 to make room for the casings 43 of the chambers 20. This piston also has a central chamber 44 to make room for a central casing 45 of the chamber 19 of the interposed wall. Further the piston member 7 is provided with a valve 46 having a stem 47 whose upper extremity is connected with the piston member by a screw 48 threaded into the stem as shown at 49. The head of this screw extends outwardly beyond the adjacent surface of the stem and engages a spiral spring 50 located in a recess 51 surrounding the upper extremity of the valve stem. Above the head of this screw, a recess is formed in the piston member 7 and into it is threaded as shown at 52, a nut 53, a gasket 54 being employed to form a fluid tight joint. The lower extremity of the valve stem 47 is provided with an enlarged valve piece 55, which when the piston member 7 is at its outward limit of movement, engages the gasket 34 and forms a fluid tight joint, whereby the actuating fluid is cut off from the pressure surface of the piston member 7. This valve piece is of less diameter as shown at 56 than the chamber 19 in which it is located for a purpose hereinafter explained.

The lower piston member 6 is provided with two valves 57 having stems 58 whose lower extremities are connected with the lower part 59 of the piston members by screws 60 having reduced shanks which are threaded as shown at 61 into the stems. The head of each of these screws extends beyond the valve stem and engages a relatively stiff spiral spring 62. Below the head of each screw is formed a recess into which is threaded a nut 63, between which and the adjacent surface of the part 59 of the piston is located a gasket 64 whereby a fluid tight joint is formed. The upper extremity of each valve stem 58 is provided with a valve piece proper 65 which when the piston member 6 is at its outward limit of movement engages one of the gaskets 33 of the interposed wall and forms a fluid tight joint to cut off the actuating fluid from the pressure surface of this piston member.

When the cartridge is in use, actuating fluid as water, enters the cartridge bar through a conduit 66 which communicates at its inner extremity as shown at 67 with a passage 68 which communicates with a passage 69 formed in a relatively small conduit 70 inserted and fastened in a longi-

tudinal recess 71 formed in the bar. The water after entering the passage 69 passes through a branch passage 72 which extends upwardly and communicates as shown at 73 with the outer extremity of a passage 70 74 whose inner extremity communicates as shown at 75 with a short angular passage 76 formed in the pin 18 which passage communicates with the upper extremity of a vertically disposed passage 77 formed in the 75 interposed wall and which communicates at its lower extremity with a horizontally disposed passage 78 which communicates at its inner extremity as shown at 79 with a valve chamber 20 of the interposed wall. 80 It should be understood that the actuating fluid as water enters at each extremity of the interposed wall, the corresponding ports and passages being indicated by the same reference characters. Hence the actuating 85 fluid simultaneously enters the two valve chambers 20 and passes downwardly through the grooves 32 formed in the nuts 30, to the pressure surface 80 of the piston member 6. Furthermore this actuating fluid passes from 90 the valve chambers 20 of the interposed wall through passages 81 of the interposed wall, into the central chamber 19 of said wall, and thence upwardly through the recesses 24 of the nut 21, to the pressure surface 95 82 of the piston member 7 and into a central chamber 44 of said piston member. From this chamber the motive fluid passes into the chambers 42 of the piston member 7 and also into the chamber 12 and thence 100 to the pressure surface of the piston member 7.

By virtue of the passage of the motive fluid as water to the pressure surfaces of the two piston members, these two members will be simultaneously projected until the valve piece 55 of the member 7 and the two valve pieces 65 of the member 6 are brought into engagement with the respective gaskets 34 and 33 whereby the grooves 110 23 of the nut 21 and the grooves 32 of the nuts 30, are closed thus cutting off the supply of motive fluid from the pressure surfaces of the two piston members, and preventing further movement of these members. 115

Provision is made however by the employment of the relatively stiff spiral springs 50 and 62, for permitting a limited further travel of the piston members, in case the motive fluid should leak past the gaskets 120 33 and 34 of the interposed wall. In this event, the further movement of the piston members will be sufficient to open ports or passages formed in the cartridge bar for the escape of the motive fluid. These springs 125 constitute a safety or emergency appliance and will undoubtedly only occasionally be brought into requisition.

In the form of construction shown in Figs. 12 to 15 inclusive, the piston members 130

as well as the general construction coöperating therewith, are substantially the same so far as the general arrangement is concerned as shown in the other views, the only difference being that the piston members are cylindrical instead of ellipsoidal in shape, the interposed wall as well as the chamber in which the piston members and wall are located, being of corresponding shape and 5 may be designated by the same or corresponding reference characters. It is evident that the general feature of telescoping coöperating piston members spaced by an interposed wall having passages or a passage 10 for the introduction of the motive fluid to the pressure surfaces of the said members, may be employed where the piston members are cylindrical in shape, as well as where these members are elongated or 15 ellipsoidal in shape. Prominence has however been given in this application to the elongated form of piston members, since the special construction including the horizontally disposed pins 18 for securing the 20 interposed wall in place is specially adapted for use where this wall is elongated in shape and therefore cannot be screwed into position, as can the cylindrical form of wall. But the advantage of forming the main 25 passage or passages for the introduction of motive fluid to the pressure surfaces of the piston members, is equally important, regardless of the particular shape of the interposed wall and the telescoping piston 30 members coöperating therewith. It will be noted that in Figs. 12 and 13 of the drawing, the interposed wall 8 is provided with a passage 77 for introducing the liquid or other motive fluid on one side only of 35 this wall. This of course is an immaterial feature particularly where the piston members are cylindrical in shape. In the elongated form of construction, it is preferred to introduce the motive fluid through passages 40 at both ends of the said wall. In any event the invention is sufficiently broad to cover the introduction of the motive fluid to the pressure surfaces of the piston members by way of one or more passages formed 45 in the interposed wall. This is a distinctly novel feature and one to which attention has heretofore been called since it is preferred that the main passage for the motive fluid 50 to the pressure surfaces of the piston members should be in a stationary rather than in a movable part.

In further explanation of the differences in detail between the construction shown in Figs. 12 and 13 and that shown in the other views, it should be stated that the interposed wall is provided with a single centrally located chamber which is designated 19 to correspond with the designation of the correspondingly positioned chamber of the other views; while the chambers 20 of

the construction shown in the last named views, and their casings 43 are dispensed with it. Again the piston member 6 in Figs. 12 and 13, contains a single valve 57 only and this valve enters the central chamber 19 of the interposed wall, the bottom of the chamber 19 being formed by a nut 30 which is provided with an opening through which the stem 43 of the valve 57 passes, the upper surface of the nut having a gasket 75 which the valve piece 63 of the valve 57 engages to cut off the fluid from the pressure surface of the piston member 6. Again in order that the stem 47 of the valve 46 of the piston member 7 may assume the telescoped position, the stem 43 of the valve 57 is centrally recessed longitudinally as shown at 99 to allow the stem 47 to enter (see Fig. 12). Another detail of difference 80 consists in the fact that in the form of construction shown in Figs. 12 and 13, the motive fluid on its way to the pressure surfaces of the two piston members enters the central chamber 19 of the interposed wall and passes therefrom to the pressure surfaces of 85 both piston members 6 and 7.

From the foregoing description the use and operation of my present improvement will be readily understood. The motive fluid usually liquid and preferably water 90 by reason of its cheapness, is introduced simultaneously to the pressure surfaces of both piston members as heretofore described, and acts thereon to project these members in opposite directions. When the members have reached their limit of movement, the valves 42 and 57 carried thereby 95 serve to cut off communication between the motive fluid and the pressure surfaces of these members, with the result that the members cease to move. Provision is made however whereby the members may have a further limited movement to provide for the possible contingency that the motive fluid 100 may leak past the gaskets with which the valve pieces are in contact. In this event provision must be made for permitting the escape of the motive fluid, by the uncovering of ports formed in the cartridge bar, 105 by the further or additional movement of the piston members. Suitable ports 90 and 91 for this purpose are indicated by dotted lines in Fig. 9. The port 91 is utilized to 110 permit the escape of the motive fluid when the lower piston member 6 has moved beyond the position shown in Fig. 5, while the port or passage 90 is utilized when the piston member 7 has moved beyond the position shown in the same figure, the additional 115 movements of both pistons being permitted by the springs 62 and 50 as heretofore explained. In order that the motive fluid 120 may pass through the relief port 91, it is necessary that the piston member 6 be provided with a port 92 (see Fig. 9), which 125

when this piston member is projected far enough to require the escape of the motive fluid, the port 92 in the piston member 6 will register with the port 91 in the bar.

Having thus described my invention, what I claim is,—

1. An hydraulic cartridge including two telescoping piston members spaced by an interposed wall having a passage for conducting motive fluid to the pressure surfaces of the said members.

2. An hydraulic cartridge including two telescoping piston members spaced by an interposed stationary wall having a passage for conducting motive fluid to the pressure surfaces of the said members.

3. An hydraulic cartridge including two telescoping piston members spaced by an interposed stationary wall having passages for the introduction of motive fluid to the pressure surfaces of the said members, one piston member having a gasket engaging the said wall to form a fluid tight joint.

4. An hydraulic cartridge including two telescoping piston members spaced by an interposed stationary wall having a passage for conducting motive fluid to the pressure surfaces of the said members, the said wall and one piston member being respectively equipped with gaskets to form fluid tight joints between the piston members and the adjacent parts.

5. An hydraulic cartridge including a bar provided with a chamber, a telescoping piston located in said chamber and composed of two members, and a stationary wall separating the two piston members, the said wall having a passage for conducting motive fluid to the pressure surfaces of the two piston members.

6. An hydraulic cartridge including an elongated piston composed of two telescoping members spaced by an interposed wall of corresponding shape.

7. An hydraulic cartridge including an elongated piston composed of two telescoping members spaced by an interposed wall of corresponding shape and having a passage for conducting motive fluid to the pressure surfaces of the said piston members.

8. An hydraulic cartridge including an elongated piston composed of two telescoping members spaced by an interposed stationary wall of corresponding shape.

9. An hydraulic cartridge including an elongated piston composed of two telescoping members spaced by an interposed stationary wall of corresponding shape, said wall having a passage for conducting motive fluid to the pressure surfaces of the said piston members.

10. An hydraulic cartridge including an elongated piston composed of two telescoping piston members spaced by an interposed stationary wall of corresponding shape, one

piston member having a gasket engaging the said wall to form a fluid tight joint.

11. An hydraulic cartridge including an elongated piston having two telescoping members spaced by an interposed wall of corresponding shape, the said wall and one piston member being respectively equipped with gaskets to form fluid tight joints between the piston members and the adjacent parts.

12. An hydraulic cartridge including a bar having a chamber, a wall separating the chamber into compartments, and pins anchored in the bar and engaging perforations formed in the said wall for securing the latter in position, and piston members arranged in the respective compartments of the chambers.

13. An hydraulic cartridge including a bar having an elongated chamber, a wall of corresponding shape separating the chamber into compartments, and pins anchored in the bar and engaging perforations formed in the said wall at its opposite extremities for securing the latter in position, and piston members arranged in the opposite extremities of the chamber.

14. An hydraulic cartridge comprising a bar having a plurality of chambers arranged at suitable intervals, walls arranged in said chambers, each wall separating its chamber into two compartments, pins passed through perforations formed in the adjacent portions of the bar and the extremities of the said walls which secure the latter in place, and piston members located in the respective compartments of the chamber.

15. An hydraulic cartridge comprising a bar having a plurality of elongated chambers, interposed walls of corresponding shape located in the respective chambers and separating each chamber into two compartments, pins engaging registering perforations formed in the adjacent extremities of the interposed walls of any two chambers, the adjacent portion of the bar being likewise perforated and pierced by the securing pin, and piston members located in the respective compartments of each chamber.

16. An hydraulic cartridge including a bar having a chamber, a wall separating the chamber into two compartments, piston members located in the respective compartments, means for introducing motive fluid to the respective compartments for the projection of the piston members, and means carried by the piston members for automatically cutting off the supply of fluid from the pressure surfaces of the said members when they have reached a predetermined limit of outward travel.

17. An hydraulic cartridge including a bar having a chamber, a wall separating the chamber into two compartments, piston members located in the respective compart-

ments, means for introducing motive fluid to the respective compartments for the projection of the piston members, and means carried by the piston members for automatically cutting off the supply of fluid from the pressure surfaces of the said members when they have reached a predetermined limit of outward travel, the cartridge bar being provided with normally closed relief ports, and means for permitting the further movement

of the piston members to uncover these ports in case the motive fluid leaks past the means for automatically cutting off the supply substantially as described.

In testimony whereof I affix my signature in presence of two witnesses.

DAVY VANCE SICKMAN.
